UNITED STATES PATENT OFFICE.

MERTON T. STRAIGHT, OF ADEL, IOWA, ASSIGNOR TO HALVER R. STRAIGHT, OF ADEL, IOWA.

MACHINE FOR CORRUGATING PLASTIC BLOCKS.

1,411,535.

Specification of Letters Patent.

Patented Apr. 4, 1922.

Application filed June 20, 1919. Serial No. 305,510.

To all whom it may concern:

Be it known that I, MERTON T. STRAIGHT, a citizen of the United States, residing at Adel, in the county of Dallas, State of Iowa, 5 have invented a Machine for Corrugating Plastic Blocks, of which the following is the specification.

This invention relates to improvements in clay working machines and particularly to 10 those designed to corrugate the ends of tile and hollow building blocks. Heretofore the tile and building blocks have been cut with comparatively smooth ends. In drain tile it is desirable to corrugate or groove the 15 ends to permit water to flow more freely between the adjacent ends when laid in the ditch. In building blocks it is desirable to corrugate or groove the ends to permit the mortar and cement to adhere more firmly, 20 when the blocks are laid in a wall.

The object of my invention is to provide a machine of simple, durable and inexpensive construction adapted to automatically form grooves or corrugations in the ends of 25 blocks formed of plastic material.

A further object is to provide in connection with a belt for conveying plastic blocks, means for automatically corrugating the upper and lower ends of the block carried 30 thereby.

A further object is to provide in a device for corrugating plastic blocks carried by a conveyor belt, new and improved means for timing and driving the devices from said 35 belt.

A still further object is to provide in a device for corrugating plastic blocks by means of spaced corrugated rollers, improved means for preventing the plastic material 40 from sticking to the grooves in said rollers as they are being operated.

My invention consists in the construction, arrangement and combination of the various parts of the device whereby the objects contemplated are obtained as hereinafter more 45 fully set forth, pointed out in my claims and illustrated in the accompanying drawings in which:

Fig. 1 is a central longitudinal sectional view of my improved corrugating machine showing the manner in which the blocks are conveyed between the rollers.

Fig. 2 is a transverse sectional view taken on the line 2—2 of Fig. 1.

Fig. 3 is a detailed elevation showing the

left hand side of Fig. 2 and the portion of the supporting frame.

Fig. 4 is a perspective view of a tile that has been corrugated by my device showing the manner in which the grooves or corruga- 60 tions are placed thereon.

In the illustration of my invention disclosed in the accompanying drawings, I have used the reference numeral 8 to indicate parallel supporting members provided with 65 legs 9 and connected together by means of transverse members 10. Each of the side members 8 is provided with a notch 11 in its upper edge.

Rotatably mounted in each end of the 70 members 8 is a shaft 13, each of which is designed to carry a pulley wheel 14, one of the shafts 13 being extended laterally from the side of the frame and provided with a belt wheel 15.

Rotatably mounted in the upper edges of 75 the members 8 adjacent to the notch 11, are transverse rollers 16. Similar rollers 17 are provided at substantially equidistances between the rollers 16 and the pulleys 14. 80

Rotatably mounted at a point below and between the pulleys 16 is a shaft 18, one end of which is provided with a belt pulley 19. A gear wheel 20 is secured to the shaft 18 adjacent to the inner side of one of the 85 members 8. Secured to one end of the central portion of the shaft 18, I have provided a disc 21 provided with a series of laterally extending bars 22 which are spaced apart and arranged parallel to each other and parallel 90 with the shaft 18. The opposite ends of the bars 22 are held in position relative to each other by means of the ring 22^a. Secured to the shaft 18 inside of the bars 22, I have provided an auger 23, of such a diameter as 95 to engage the bars 22. These bars 22 and disc 21 form a drum, the purpose of which will be more fully set forth.

Mounted upon the pulleys 14, I have provided a belt 23^a, the upper run of which is 100 designed to rest on the upper sides of the rollers 17 and extend downwardly between the rollers 16 and beneath the drum formed by the bars 22. For sake of convenience, I shall call this drum a driving pulley. 105

Secured to the outsides of one of the members 8 and extending across the opening 11, I have provided a bar 24 held in position by means of bolts 25. (Fig. 3.) The bar 24 is provided with an upwardly extending 110

member 26 having a bearing 27 at its upper end, and at the intersecting portions of the bars 24 and 26 a bearing 28. Secured to the opposite member 8, I have provided an upright member 29 somewhat similar to the member 26 and provided at its upper end with the bearing 31 and at its intersecting portion provided with a bearing 32. This member 29 is provided with an opening 32^a, the lower side of which is provided with the shelf 30.

Rotatably mounted in the bearings 27 and 31, I have provided a shaft 33 having on one end a pulley wheel 34. This pulley 34 is in line with the pulley wheel 19 before mentioned. Secured to the central portion of the shaft 33, I have provided a cylindrical drum 35, the periphery of which is provided with teeth or grooves 36. These teeth are comparatively close together and extend circumferentially around the drum. The drum is formed hollow and provided with spokes 36^a, the ends being otherwise open. Thus it will be seen I have provided a hollow space through which heated air may be conducted by means of any convenient burner such as a blow torch and indicated by the numeral 37.

Rotatably mounted in the bearings 28 and 32, I have provided a somewhat similar and smaller drum than the one indicated by the numeral 35, one end of which is provided with a gear 39. This gear 39 is designed to mesh with the gear 20 before described. A blow torch 43, similar to 37, is employed for heating this drum also. A belt 40 is operatively mounted upon the pulleys 19 and 34.

In operation, assuming that the belt wheel 15 is connected with suitable power and is being rotated, and that the tile or blocks are being placed upon the belt 23^a, by hand or otherwise and in a vertical position, it will be seen that the said belt will be rotated and moved in a direction as indicated by the arrow. The rotation of the belt 23^a will cause the driving drum 21 to be rotated and the gears 20 and 39 rotated. The tile or block thereon will also be advanced toward the drums 35 and 38. This will cause the upper face of the drum 38 to be rotated in the same direction as the horizontal portion of the belt 23^a. The drum 35 will also be rotated in the opposite direction from the drum 38 by means of the belt 40, the peripheral speed of the drum 35 and 38 being substantially equal to that of the belt 23^a. Thus it will be seen that as the said belt and drums are rotated, the tile or blocks 44 will be advanced and caused to travel between the drums 35 and 38. The distance between the said drums is substantially equal to the length of the blocks, parallel grooves or corrugations will therefore be formed on the ends of the plastic tile or blocks.

To prevent the plastic clay or material

from sticking between the teeth of the drums 35 and 38, I have provided the torches 37 and 43 before mentioned. They are so arranged that the air within the drums will become heated and heat the teeth, causing a film of steam to be generated when engaged by the moist material. This steam prevents the material from sticking to the teeth.

To prevent the driving drum or roller 21 from lapping or winding with the fragments 75 of the soft material, I have provided the slats 22. These will permit the material to be forced between them which will be moved longitudinally towards the open end by means of the auger 23 as it is rotated.

Thus it will be seen that I have provided a machine of comparatively simple and inexpensive construction adapted to corrugate the ends of plastic tile or blocks.

I claim:

1. In a device of the class described, a support, a conveyor belt operatively mounted thereon, means for driving said belt, means for forming a loop in one of the runners of said belt, a corrugated roller in 90 said loop, a second corrugated roller, and means for driving said corrugated rollers in opposite directions as the conveyor belt is operated.

2. In a device of the class described, horizontal and parallel supports, a transverse roller at each end of said support, central spaced transverse rollers, a driver roller beneath and between said central rollers, a belt wheel on one end of said driver roller 100 shaft, a gear on said driver roller shaft, a conveyor belt running beneath and over the end rollers and over and between the central rollers and beneath the driver roller, a corrugated roller between the central rollers 105 having its upper face substantially level with the upper run of the conveyor belt, a pinion on said corrugated roller in mesh with the said gear, a second corrugated roller above and parallel with the said first 110 corrugated roller, a belt wheel on the end of said upper corrugated roller, a belt for said belt wheels, and means for driving said end rollers.

3. In a device of the class described, horizontal and parallel supports, a transverse roller at each end of said support, central spaced transverse rollers, a driver roller beneath and between said central rollers, a belt wheel on one end of said driver roller shaft, 115 a gear on said driver roller shaft, a conveyor belt running beneath and over the end rollers and over and between the central rollers and beneath the driver roller, a corrugated roller between the central rollers having its 120 upper face substantially level with the upper side of the conveyor belt, a pinion on said corrugated roller in mesh with the said gear, a second corrugated roller above and parallel with the said first corrugated roller, a 125

130

belt wheel on the end of said upper corrugated roller, a belt for said belt wheels, means for driving said end rollers and means for heating the said corrugated rollers.

- 5 4. In a device of the class described, horizontal and parallel supports, a transverse roller at each end of said support, central spaced transverse rollers, a driver roller beneath and between said central rollers, said 10 driving roller being formed of spaced bars and provided with a central means for advancing material, that has passed between the bars, longitudinally and discharging it at one end, a belt wheel on one end of said 15 driver roller shaft, a gear on said driver roller shaft, a conveyor belt running beneath and over the end rollers and over and between the central rollers and beneath the driver roller, a corrugated roller between 20 the central rollers having its upper face substantially level with the upper side of the conveyor belt, a pinion on said corrugated roller in mesh with the said gear, a second corrugated roller above and parallel with 25 the said first corrugated roller, a belt wheel on the end of said upper corrugated roller, a belt for said belt wheels, means for driving said end rollers and means for heating the said corrugated rollers.
- 30 5. In a device of the class described, a support, a conveyor belt operatively mounted thereon, means for driving said belt, means for forming a loop in one of the runners of said belt, a corrugated roller in said loop, 35 a second corrugated roller, means for driving said corrugated rollers in opposite directions as the conveyor belt is operated, and means for heating each of said rollers, for the purpose stated.
- 40 6. In a device of the class described, a support, a conveyor belt, end rollers for said belt, intermediate rollers for one runner

of said belt, a roller below and between two of said intermediate rollers, for forming a loop in said belt, a corrugated roller in said 45 loop, having one side even with the looped runner, a second spaced corrugated roller, means for driving said corrugated rollers in opposite directions, and means for driving said conveyor belt.

50 7. In a device of the class described, a conveyor belt having a downwardly projecting loop in its upper runner, means for supporting and driving said conveyor, a corrugated roller in said loop, having its 55 upper face even with the face of said looped member, a second spaced corrugated roller parallel therewith, means for driving the said corrugated rollers in opposite directions as the said conveyor belt is driven.

60 8. In combination, a belt conveyor, a series of parallel supporting rollers, a roller below and between two of said parallel rollers, for forming a loop in said belt, said roller comprising a circular end plate and 65 an annular member, a series of spaced bars arranged cylindrically for connecting said end members, and a central shaft for said roller.

70 9. In combination, a belt conveyor, a series of parallel supporting rollers, a roller below and between two of said parallel rollers, for forming a loop in said belt, said roller comprising a circular end plate and an annular member, a series of spaced rods arranged cylindrically for connecting said end members and to permit material from the belt to pass to the interior of said roller, a central shaft for said roller, a screw member between said bars and the shaft to move 75 the collected material toward the end having the annular member, as the roller is rotated in one direction.

MERTON T. STRAIGHT.
